(57) **CLAIM**

We claim the ornamental design for a hand-held electronic device case, as shown and described.

DESCRIPTION

FIG. 1 is a front perspective view of a hand-held electronic device case;

FIG. 2 is a rear perspective view of a hand-held electronic device case;

FIG. 3 is a front view thereof;

FIG. 4 is a back view thereof;

FIG. 5 is a bottom plan view thereof;

FIG. 6 is a top plan view thereof;

FIG. 7 is a right view thereof; and,

FIG. 8 is a left view thereof.
